UNITED STATES PATENT OFFICE.

GEORGE JOHN, OF DETROIT, MICHIGAN, ASSIGNOR OF ONE-HALF TO ELEES AMOUNEY AND ONE-SIXTH TO GEORGE ASSED, BOTH OF DETROIT, MICHIGAN.

TOY TOP.

1,209,446.

Specification of Letters Patent. Patented Dec. 19, 1916.

Application filed September 8, 1916. Serial No. 119,007.

To all whom it may concern:

Be it known that I, GEORGE JOHN, a subject of the Sultan of Turkey, residing at Detroit, in the county of Wayne and State 5 of Michigan, have invented certain new and useful Improvements in Toy Tops, of which the following is a specification, reference being had therein to the accompanying drawings.

10 This invention relates to a toy top, and more particularly to a top spinning device which obviates the necessity of using a cord or string, winding the cord or string upon a top, and then throwing the top to spin 15 the same.

The object of my invention is to provide a top spinning device that may be safely held in the hand and operated to eject and impart a spinning movement to a top placed 20 on the device. To accomplish this object, I have devised a simple and inexpensive toy including a stationary spiral member on which may be threaded a top, and a latch held spring actuated member adapted to be 25 released to eject the top from the spiral member.

The construction entering into the device will be hereinafter specifically described and then claimed, and reference will now be had 30 to the drawing, wherein—

Figure 1 is a vertical sectional view of the device; Fig. 2 is a side elevation of the top, and Fig. 3 is a bottom plan of the top.

In the drawing, 1 denotes a handle having 35 a longitudinal, cylindrical recess 2, and mounted in the inner end of the recess 2 is a holder 3 for a spiral member 4 and the inner convolution of a coiled spring 5 encircling a portion of the member 4.

40 6 denotes a sleeve loose on the spiral member 4 and having the inner end thereof recessed, as at 7, to receive the outer convolution of the spring 5 and be connected thereto, as indicated at 8. The sleeve has 45 an annular shoulder 9 adapted to be engaged by a latch 10 pivotally held as at 11, between ears 12 of a ferrule 13, said ferrule being mounted on the outer reduced end of the handle 1. A piece of rubber 14 50 is placed between the ears 12 of the ferrule 13 to hold the latch 10 normally in engagement with the sleeve 6. A flat or coiled compression spring will serve the same purpose as the piece of rubber 14.

15 denotes a conical shaped top having 55 a central longitudinal bore 16 with one end thereof provided with a metallic liner 17 and the opposite end with a cup shaped nut 18. The liner 17 prevents excessive wear upon the top of the top when being ejected 60 from the member 4, and the cup shaped nut 18 has an opening 19 corresponding in area to the cross sectional area of the member 4. The nut 18 closes the end of the core 16, with the exception of the opening 19, and 65 centrally of said nut is a bearing point 20 corresponding to the plug of an ordinary spinning top.

To place the device in operation, the handle 1 is held in one hand and the other 70 hand used to lower the sleeve 6 on the member 4 until the latch 10 springs into engagement with the annular shoulder 9 of the sleeve, at which time the spring 5 is under compression. The top 15 is next threaded 75 on the upper end of the member 4 and allowed to descend by gravity until the spinning point 20 rests on the outer end of the sleeve 6. By then holding the device in a vertical position or at an inclination to 80 discharge the top 15 in a desired direction, the latch 10 is actuated to release the sleeve 6. The expansive force of the spring 5 will project the sleeve 6 outwardly on the member 4, causing the top 15 to revolve by 85 reason of its threaded connection with the member 4 and eventually ejecting the top from the end of the member. The top will spin on the surface to which it is directed and the device may be reset for another 90 operation.

What I claim is:—

A top spinning device comprising a handle having a longitudinal recess, a spiral member extending into the recess of said handle and having the inner end thereof fixed in the closed end of said recess, a sleeve loose upon said spiral member and provided with an annular shoulder, said sleeve having a recess in the inner end thereof, a coiled compression spring having the outer end thereof mounted in the recess of said sleeve and the inner end thereof fixed in the inner end of the recess of said handle, and adapted to be housed thereby, a ferrule on said handle, a pivoted latch carried by said ferrule and adapted to engage the shoulder of said sleeve and hold said spring

under compression, a top having a longitudinal bore, and a nut in the inner end of said bore threaded on said spiral member and providing a bearing point for engagement with the outer end of said sleeve so that by releasing said latch, said sleeve may eject said top from said spiral member.

In testimony whereof I affix my signature in presence of two witnesses.

GEORGE JOHN.
